Benjamin Gates, of Hallowell, Maine

Sellers Patent

The Schedule referred to in the Sellers Patent and making part of the same containing a description in the words of the late Benjamin Gates himself of his improvement in the Cullup Chain Horse Power

Dedication

It is known that Benjamin Gates of Hallowell in the County of Kennebec and State of Maine have invented a new and useful improvement in the "Horse Power" and that the following is a full and exact description

thereof Fig. 1 of the accompanying drawings which are referred to and made a part of this description represent the whole of his improvement for operation and consists of a frame to which two four horizontal bars 10 inches apart long, and four cross bars 10 feet long, and six upright posts with rim pieces running the whole length of the frame. The length of the side bars give the length of the machine and the cross bars breadth. Which may be varied suit those who use the same.

Fig. 1 represent the bars in the chain which are to be of wood or may be either of cast or straight iron or a part of either and made just at both ends to the thickness of the chain Fig. 2. represent the two wheels on which the chain passes which are to be made of cast iron six inches in diameter.

Fig. 3. represents two smaller wheels six inches in diameter. Two of which are to support the chain in the center, standing on plank, running from one of the two smaller to the other and supported in a frame. Fig. C represents the chain in its place, which is formed by a succession of hinge pieces connected together so as to form an endless chain this is to consist of cast iron or other suitable material. Fig. D represents the whole of part from the machine which has on its outer edge a flange of iron or projection to meet and support each link of the chain and project it to its reception.

Fig. E represents two links of the chain separately and Fig. F represents them connected together forming a hinge piece. Fig. G, H, I, J,

represent the form of one of the links with the pins, &c. which are intended to enter the corresponding openings b, b, when the links are put together as in Fig. 1, Fig. 5, 5, of C and b of D, represent the form of the corresponding link with the orifices. The end of one of the links may be formed with a triangular head or tongue with a shoulder made to fit into a notch in the end of the corresponding link and the two connected together by the pins, &c. and when thus coupled make one piece of the chain as the end, the link 4, with the pins, &c. may pass it leaving a shoulder which meets a corresponding projection and shoulder in 5 with the orifice, the two ends of the corresponding links being halved together and fastened with the pins, &c. and when thus united forming one piece of the chain and so the bridge piece after one thus coupled with the whole suspension is formed into an anchor chain. This latter form is adopted in the middle and drawings. When worked the two being together make a firm support for the turn where power is to turn the chain, and when drawn upon the shaft above described. The number of wheels under the chain may be more than they are intended as well to keep the chain in its place and prevent vibration as to sustain it. The chain as it passes over the wheel forms a railway as is shown at Fig. 6 of D and this railway is a part of the link of the chain and is cast with it. The projections of the links of the chain fitting with the corresponding indentures between the tops of the end wheels, in section to the thin wheels and the machinery attached to it, and the pins are communicated to machinery by means of a cog wheel or bar which is attached to the shaft of either of the wheels 22. The pin a, in 4 of Fig. C, may be cast with the link or it may be of wrought iron and driven through both ends of the link or the bar may be fastened with a screw. I claim also and of my own invention both described modes of forming the hinge and the peculiar form of the link. I claim the forming of the end wheels with the tops of projections & the mode of communicating power by the projections of the chain fitting into the indentures between the projections of the wheels. I also claim the mode of sustaining the chain and keeping it in its place by means of the railway and small wheels as above described.
